George C. Hockenberger Inventor

By John W. Sharley.
Attorney

UNITED STATES PATENT OFFICE.

GEORGE C. HOCKENBERGER, OF BRIDGEPORT, CONNECTICUT, ASSIGNOR TO POOLE ENGINEERING AND MACHINE COMPANY, OF BALTIMORE, MARYLAND, A CORPORATION OF MARYLAND.

WRINGER HOUSING FOR WASHING MACHINES.

Application filed August 16, 1923. Serial No. 657,658.

To all whom it may concern:

Be it known that I, GEORGE C. HOCKENBERGER, a citizen of the United States, residing at Bridgeport, in the county of Fairfield and State of Connecticut, have invented certain new and useful Improvements in Wringer Housings for Washing Machines; and I do hereby declare the following to be a full, clear, and exact description of the invention, such as will enable others skilled in the art to which it appertains to make and use the same.

My invention relates to wringer housings for washing machines.

15 Among the objects of my invention are:—

To provide a wringer housing for washing machines which can be readily machined and readily assembled.

To provide a wringer housing for washing machines providing for greater freedom of movement of the wringer supporting frame so that it may be positioned in any one of a plurality of positions.

To provide a wringer housing which can be readily assembled in combination with a center housing arranged to cooperate therewith.

These and further objects of my invention will be set forth in the following specification, reference being had to the accompanying drawing and the novel means by which said objects are effectuated will be definitely pointed out in the claims.

In the drawings:—

35 Figure 1 is a central sectional elevation of my improved wringer housing.

Fig. 2 is a view of some of the parts shown in Fig. 1 looking in the direction of the arrow 2 in said figure.

40 Fig. 3 is a section along the line 3—3 in Fig. 1 looking in the direction of the arrows.

Fig. 4 is a view of the parts shown in Fig. 1 looking in the direction of the arrow 4 in said figure.

Fig. 5 is a section along the line 5—5 in Fig. 1 looking in the direction of the arrows.

In the drawings:—

50 10 represents a portion of a suds container upon which my improved wringer is usually mounted. The casing 11 of my wringer housing is secured to the suds container

by bolts such as 12 and said casing is provided with a wringer bearing 13 in which 55 the wringer sleeve 14 is revolvably mounted.

An index pin 15 is slidably mounted in the casing 11 and pressed towards the sleeve 14 by the spring 16, a knob 17 serving to provide means for withdrawing said pin 60 from index holes such as 18, any desired plurality of which can be provided in the sleeve 14. The sleeve 14 is provided with a groove 19 for a purpose hereinafter explained, and is also provided with a shoulder 20 which 65 rests upon a shoulder at the top of the casing 11.

The sleeve 14 is provided with a pinion bearing 21 which is coaxial with the pinion bearing 22 formed in the casing 11, and bevel pinions 23 and 24 are each provided with hubs which are revolvably mounted respectively in said bearings. The hub of the pinion 23 is provided the groove 25 and the point of the screw 27 enters said groove to 75 prevent end motion of said pinion. The screw 27 is mounted in the sleeve 14.

The pinions 23 and 24 are each provided with square axially disposed holes and the square shaft 29 has its ends mounted 80 in said holes. Pins 30 and 31 prevent undue displacement, respectively, upward and downward of said shaft.

A bevel pinion 32 is provided with a hub that is revolvably mounted in the bearing 33 85 formed in the wringer frame 34 and said pinion is prevented from moving axially by the point of the screw 35 which extends into the groove 36 formed in the hub of said pinion. 90

The wringer shaft 37 fits loosely in a cylindrical hole 38 formed in the hub of the pinion 32 and said pinion drives the shaft 37 through the pin 39 which is fast in said shaft and located within the slot 40 formed 95 in the hub of the pinion 32.

The sleeve 14 is formed integrally with the gear housing 14^a at the upper end thereof.

The wringer frame 34 is secured to said 100 gear housing by bolts such as 41 and the top of said gear housing is closed by the cover 42. The wringer frame 34 is provided with an extension 43 which is used for the support of a drip pan or other device for 105 catching the water wrung from the clothes.

These features, however, form no part of my present invention and have not been illustrated.

The pinion 24 is driven by the pinion 45 and the latter is provided with a hub that is revolubly mounted in the bushing 46. A screw 47 mounted in said bushing extends into a groove formed in the hub of the pinion 45 and prevents endwise motion of said pinion.

The bushing 46 has a cylindrical portion 48 that is larger in diameter than the largest diameter of the pinion 45 and said cylindrical portion fits snugly in a hole provided in the casing 11, the shoulder 49^a of said bushing fitting snugly against a flat surface formed on said casing.

The pinion 45 is provided with a central cylindrical hole in which is loosely mounted the wringer driving shaft 49, a pin 50 fitting tightly in said shaft and loosely in holes provided in the hub of the pinion 45 to produce a driving connection between said shaft and said pinion.

The shaft 49 is driven by the sleeve 51 and the latter is revolubly mounted in a bearing provided in the center housing 52 of the washing machine. The center housing 52 being the subject of a patent application executed on even date herewith is not completely illustrated.

The bushing 46 and housing 52 are provided with counterbored recesses for the reception of the shield tube 53, and cork washers such as 54—54 are mounted between the ends of said tube and said recesses for a purpose hereinafter explained.

The manner of assembling my improved wringer housing is as follows:—

The center housing 52 is first secured to the suds container 10 and the sleeve 51 is assembled with the housing 52 as set forth in the application for U. S. Letters Patent above referred to. The shaft 49 is then assembled with the sleeve 51 by driving the pin 54 through the holes in said sleeve into a tightly fitting hole in the shaft 49.

The tube 53 is cut approximately of the proper length and mounted within the recesses formed within the bushing 46 and housing 52. The bushing 46 is still unassembled with the casing 11 and the screws 47 and 55 are not yet in place, the latter having a pin which extends into the groove 56 of the sleeve 51 and normally prevents endwise motion of the sleeve 51. The casing 11 is then assembled with the bushing 46 and said casing is applied to the suds container to ascertain if the holes in said casing for the bolts 12 register with the corresponding holes in the suds container. If they do and the tube 53 does not hold the shoulder 49^a against the corresponding flat surface on the casing 11, then washers similar to 54 are to be placed between the tube 53 and the ends

of the recesses in the bushing 46 and center housing 52. If the holes in the casing 11 for the bolts 12 do not register with the corresponding holes in the suds container when the shoulder 49^a is against the corresponding surfaces of said casing, then the tube 53 is to be shortened until said holes do register.

In either case, when the casing 11 is mounted on the suds container 10, the function of the tube 53 is to hold the shoulder 49^a against the corresponding surface of said casing. After the tube 53 is made of the proper length or the proper number of washers 54 for insertion within the recesses 80 has been determined then the pin 50 can be driven in the shaft 49 to couple said shaft with the pinion 45. This is accomplished by removing the casing 11 and drawing the shaft 49 sufficiently beyond the extreme upper surface of the bushing 46 to enable said pin to be so driven. The cork washers 54 also act to prevent leakage of oil.

After the pin 50 is driven in place the pinion 45 and shaft 49 are moved downwardly and towards the left, the screw 47 is inserted to hold said pinion in place and the screw 55 is inserted to hold the sleeve 51 in place. The casing 11 with the other parts assembled therein can then be bolted in position. The outside diameter of the pinion 45 being smaller than the diameter of the cylindrical portion 48, it is evident that said pinion will readily pass through the hole in the casing 11 which fits said portion.

The other parts of the wringer housing are assembled as follows:—It being understood that the casing 11 is not yet assembled with the bushing 46, the hub of the pinion 24 is placed in the bearing 22. The pinion 24 can be readily assembled as just described through the opening in the casing 11 which is afterwards covered by the plate 57. The shaft 29 is then placed in the pinion 24. The shaft 37 is placed in the wringer frame 34 and the pinion 32 is then placed with its hub in the bearing 33 and the sides of the slot 40 embracing the pin 39. The screw 35 is then put in place.

The pinion 23 is passed through the opening which is afterwards closed by the cover 42 and the hub of said pinion is mounted in the bearing 21. The screw 27 is then put in place to keep said pinion from moving endwise. The sleeve 14 is then mounted in the bearing 13 and during this movement the shaft 29 is guided within the square hole in the pinion 23. The frame 34 is then assembled with the gear housing 14^a which can readily be effected since the largest diameter of the cylindrical portion 57 on said frame is larger than the largest diameter of the pinion 32 and said cylindrical portion fits snugly within a hole provided

in the gear housing 14^a. The pin 15 and its appurtenant parts are then assembled.

Thus it will be seen that I provide a simple, cheap and efficient wringer housing 5 which can be assembled with a minimum of effort.

I claim:—

1. The combination with a casing provided with a wringer bearing and a wringer sleeve revolvably mounted therein, said casing and sleeve having aligned bearings, of pinions having hubs revolvably mounted in said bearings, the hub mounted in said sleeve comprising a groove, a screw in said sleeve 10 having a point extending into said groove to prevent axial movement of said hub, said pinions comprising co-axial square holes, a square shaft mounted in said holes to couple said pinions together, a wringer driven by 15 one of said pinions and means for applying power to the other of said pinions.

2. The combination with a casing provided with a wringer bearing and a wringer sleeve revolvably mounted therein, said casing and sleeve having aligned bearings, of pinions having hubs revolvably mounted in said bearings, the hub mounted in said sleeve comprising a groove, a screw in said sleeve having a point extending into said groove 20 to prevent axial movement of said hub, said pinions comprising co-axial square holes, a square shaft mounted in said holes to couple said pinions together, a wringer driven by one of said pinions, means for applying 25 power to the other of said pinions, and pins in said shaft adjacent the hubs of said pinions to limit axial movement of said shaft.

3. The combination with a wringer sleeve 30 comprising a bearing, a gear housing having a bored opening whose axis is at an angle to the axis of said bearing, a wringer frame having a cylindrical portion mounted in said bored opening and comprising a bearing, pinions having hubs comprising grooves revolvably mounted in both said bearings, said housing having an opening opposite 35 said first named bearing to permit the insertion of one of said hubs into said first named bearing, screws in said sleeve and frame having points extending into said grooves to prevent axial movement of said hubs, a wringer driven by the pinion having the hub mounted in said frame and means 40 for driving the other of said pinions.

4. The combination with a wringer sleeve comprising a bearing, a gear housing having

a bored opening whose axis is at an angle to the axis of said bearing, a wringer frame having a cylindrical portion mounted in said bored opening and comprising a bearing, pinions having hubs comprising grooves revolvably mounted in both said bearings, said housing having an opening opposite 60 said first named bearing, screws in said sleeve and frame having points extending into said grooves to prevent axial movement of said hubs, the pinion having the hub mounted in said frame having a slot, a central cylindrical hole, a shaft having one end 65 mounted in said slot, a pin in said shaft mounted in said slot, a pin in said shaft engaging the sides of said slot and means for driving the other of said pinions.

5. The combination with a suds container, a wringer casing mounted on said container and comprising a bearing, a pinion having a hub revolvably mounted in said bearing, of a center housing mounted on said suds container, said casing comprising a bored orifice, a bushing in said orifice, 70 said bushing and housing comprising aligned recesses, a tube having its ends mounted in said recesses, washers between the ends of said tube and the bottoms of said recesses to determine the distance between said bushing and housing, a pinion having a hub mounted in a bearing formed in said bushing and meshing with said first named bushing, and a shaft having a driving connection with said last named pinion 75 80 and extending through said tube and connected to mechanism extending into said housing.

6. The combination with a suds container, a wringer casing mounted on said container and comprising a bearing, a pinion having a hub revolvably mounted in said bearing, of a center housing mounted on said suds container, said casing comprising a bored orifice, a bushing in said orifice, 90 said bushing and housing comprising aligned recesses, a tube having its ends mounted in said recesses, cork washers between the ends of said tube and the bottoms of said recesses to prevent leakage of oil, a pinion having a hub mounted in a bearing formed in said bushing and meshing with said first-named bushing, and a shaft having a driving connection with said last-named pinion and extending through said tube and connected to mechanism extending into said housing.

In testimony whereof, I affix my signature.

GEORGE C. HOCKENBERGER.
